HYDROPNEUMATIC PRESS

David E. Gray, Corning, N. Y., assignor to Corning Glass Works, Corning, N. Y., a corporation of New York

Application August 27, 1940, Serial No. 354,450

7 Claims. (Cl. 60—54.5)

The present invention relates to fluid operated presses and particularly to presses wherein certain operations are performed hydraulically and others pneumatically. Hydraulic presses of conventional designs cannot be conveniently shifted from one operating location in a plant to another as is often desirable owing to the necessity of quite elaborate plant equipment to supply the liquid employed in operating such a press or if they include independent sources of liquid supply the weight is excessive. It is possible to manufacture presses to operate pneumatically in a desired fashion but, owing to the fluidity or lack of viscosity of air, parts manufactured to operate in an exacting manner must be made with great care, as slight variations in size of ports and conduits, as well as the lengths of the conduits, are likely to alter the operating characteristics to an objectionable extent. Also, since air is compressible there results a resiliency in operation which is undesirable in glass pressing. A liquid operated press, on the other hand, has the advantage that the adjustment of control valves, etc., may be much coarser than in the case of a pneumatic press and therefore, conversely, the controls may be adjusted to a much greater degree of accuracy and much greater pressures may be utilized. The difference is of the order of 15 to 1.

A prime object of the present invention is an improved hydropneumatic press mechanism.

Another object is a press mechanism having the operating advantages of hydraulic power and and portability of pneumatically or mechanically operated press.

A further object is a press in which the movement of a mold plunger into and out of an associated mold can be effected in the exact manner known to produce best results.

Other objects and features of the invention will become apparent from a study of the embodiment of the invention herein illustrated and described.

The invention is illustrated and described as embodied in a glass pressing mechanism associated with a table carrying a plurality of molds which, in any conventional manner (not shown), are successively charged with a gob of molten glass and then brought into register with a forming plunger carried by that part of the press mechanism in which the present invention is embodied.

In the accompanying drawings:

Fig. 1 is a front elevational view of the press mechanism;

Fig. 2 is a sectional side elevation of the same; Fig. 2a and Figs. 3-6 are sectional views of various operating parts of the mechanism;

Fig. 7 is a diagrammatic view illustrating the air passage arrangement of a rotary stroke valve of the mechanism;

Fig. 8 is a schematic view illustrating the interconnection of pipes between the several operating mechanisms;

Fig. 9 is a fragmentary view of the mechanical linkage between the crosshead and the rotary stroke valve; and

Fig. 10 is a diagram designating the mechanism by means of which the rotary stroke valve is advanced to its several positions.

In brief, in the present embodiment of the invention, a pressing cycle is initiated through the medium of a pilot valve actuated each time a newly charged mold is brought into register with the forming plunger of the press mechanism. The actuation of this pilot valve causes a kicker, hereinafter referred to as a table kicker, to advance a five position rotary control valve from its position 1 to its position 2. In position 2 this valve connects a ram cylinder, previously charged with compressed air, with a low pressure liquid supply chamber to force liquid therefrom to a cylinder to lower a crosshead carrying the forming plunger. The crosshead is so mechanically linked to the rotary valve that after approximately five-sevenths of the downward movement of the crosshead such valve is brought to position 3 and near the end of the downward movement is advanced to position 4. In position 3 the valve connects a head of air directly to the low pressure chamber insuring continuance of the downward movement of the crosshead, and in position 4 supplies air to a high pressure cylinder to operate a ram which increases the downward pressure on the crosshead beyond that exerted by application of air to the low pressure chamber and finally in its lowering movement increases such pressure to a maximum desired value. After a predetermined pressure has been

developed, a second kicker, hereinafter referred to as a pressure kicker, is actuated under control of a pressure adjuster and pressure kicker valve to advance the rotary stroke valve to position 5. The rotary stroke valve in position 5 connects all air supply lines extending to the press operating mechanism to atmosphere, so that all downward pressure by the crosshead mechanism is removed excepting such as results from its dead weight and supplies air to a timer which, after the expiration of a predeter-

55

mined period of dwell of the plunger in the mold, causes a third kicker, hereinafter referred to as a timer kicker, to advance the rotary stroke valve to position 1. In this position the rotary stroke valve supplies air to the high pressure cylinder to effect the return of the ram and crosshead to their up-positions in readiness for use in a subsequent pressing cycle, whenever such cycle is initiated by advancement of a newly charged mold into register with the press mechanism.

In detail, the structure illustrated comprises a rotatable table 11 provided with suitable molds 12 which are brought, in any known manner, successively under a forming plunger 21 carried by a crosshead 22. This crosshead and the associated mechanism for operating it through a pressing cycle are carried by a frame consisting primarily of a base 25 and two upright supports 26 bridged by a table or platform 27.

The crosshead 22 closes the lower end of a crosshead actuating cylinder 30 containing a piston 31 carried by a tubular piston rod 32 the upper end or head portion 34 of which is secured to the lower side of platform 27 and is so formed as to serve as the bottom end of a low pressure fluid chamber 35 in part formed by a hole 36 through platform 27 covered by part 34 of the piston rod. A cylinder 39 whose inner wall is of the same diameter as that of hole 36 is secured to the upper side of platform 27 in register with hole 36 and is of such height as to give chamber 35 the desired capacity. The upper end of this chamber is closed by a head 40 serving as the lower head for a high pressure cylinder 41. This latter cylinder is closed at the top by a suitable head 42 and contains a ram 43 having an operating piston 44. This ram passes through head 40, the chamber 35, and on down into the central or main bore 45 of the crosshead rod 32. To lower the crosshead, liquid 13 is pneumatically driven from chamber 35 into cylinder 30 beneath piston 31. Passages for the flow of liquid from chamber 35 to cylinder 30 initially include multiple paths from chamber 35 into the bore 45 of rod 32 as well as multiple paths between the bore 45 and the cylinder area under piston 31. The one former path includes passages 46 and 47 through the lower end of ram 43 and a check valve 38 and the other comprises a by-pass passage 37 (Fig. 2a) in head portion 34 of rod 32 opening into chamber 35 and into bore 45 at a point just below the lower end of the ram in its uppermost or normal position. One of the paths between bore 45 and the lower side of piston 31 includes a row of graduated apertures 48 in rod 32 in communication with a passage 49 therein passing through piston 31. The other path is directly through an aperture 54 in the piston. That portion of cylinder 30 above its piston 31 and surrounding rod 32 is full of liquid 14 supplied to it from cylinder 41 via a path which includes a pipe 65, a regulating valve 66, a needle valve 67, a pipe 68, and a passage 69. The needle valve is normally held wide open by a spring 70, but is adapted to be almost closed through the medium of a bell crank 63 having a roller 62 engaged by an adjustable cam 61 on the crosshead as it approaches its lowermost position.

Fluid is supplied to the top of cylinder 41 to drive the piston 44 downward to lower the ram. As soon as the ram has been lowered a short distance, the by-pass 37 around check valve 38 is closed by the ram. However, liquid continues to be forced from chamber 35 through passages 46 and 47 and check valve 38 until such time as the 75

velocity of the ram equals the velocity of the flow of liquid. When this occurs check valve 38 closes and all further supply of liquid to the under side of piston 31 results from the movement of ram 43. As the ram continues downward it successively closes the ports 48 thus diminishing the speed at which the liquid is introduced to the under side of the piston 31 until finally it passes solely through aperture 64. As the crosshead approaches its lowermost position cam 61 engages roller 62 on bell crank 63 and partially closes needle valve 67 against the pressure of spring 70, thus the flow of liquid from the upper side of piston 31 is choked for the further control of the speed of liquid to the under side of the piston. The ram is raised by fluid supplied to a portion of cylinder 41 at a point below the downmost position of piston 44. When the ram has been fully raised the by-pass 37 around check valve 38 is again open. This enables the free return of the liquid in cylinder 30, in the area below piston 31, to chamber 35 by pressure developed in cylinder 41. Such pressure forces liquid 14 therefrom to the area of the cylinder 30 above piston 31 via the previously traced path to raise the crosshead. The raising movement is initially very slow as a result of needle valve 67 restricting the flow of liquid to cylinder 30 and is done to guard against deformation of freshly pressed ware such as might result if the initial upward movement of the plunger were too rapid. Subsequently the cam 61 clears roller 62 enabling valve 67 to open wide so that liquid 14 is rapidly supplied therethrough to raise the crosshead.

The operations of the crosshead and ram assemblies are under control of a rotary stroke valve 50 which comprises a cylindrical housing 51 (Figs. 4 and 9) with outlets having connected pipes 52-58, as designated in Fig. 7, and contains a drum suitably grooved to selectively establish communication between the housing outlets. This drum designated with the numeral 59 is diagrammatically illustrated in Fig. 7 wherein its five different positions relative to the housing outlets are illustrated. A shaft 60 (Figs. 4 and 9) connected with the drum 59 of the rotary valve 50 projects out through the end of its housing and affords a means by which the drum can be rotated through its various operating positions. Movement of the drum from position 1 (its normal position) to position 2 is effected by a mechanism hereinafter referred to as the table kicker 71 (Figs. 1 and 4). This mechanism comprises a single notch disc 75 fixed to shaft 60 and a pawl 76 so associated therewith that it can be lowered into the notch of disc 75 when the drum is in position 1 and can then be raised to advance the drum to position 2. The pawl 75 is carried by an arm 77 having one end freely supported by shaft 60 and having its other end connected to a link 82 suspended from the lower end of a pneumatically operable connecting rod 83 (Fig. 4). An intermediate portion of this rod is provided with a piston 85 operative in a cylinder 86 and with the upper end of rod 83 projecting into a relatively small diameter cylinder 87. The top of the upper cylinder 87 is connected with a branch pipe 101 of a high pressure air supply line 100 (Fig. 1), so that a head of air is permanently maintained in cylinder 87 and tends to drive the rod 83 down to a position to register with the notch in disc 75. The lower and larger diameter cylinder 86 at its bottom end is connected with a pipe 103 to which air can be sup-

plied to drive the rod upward to advance the rotary stroke valve drum to position 2.

To move the drum from position 2 to position 4, shaft 60 is provided with a single notch disc 91 (Fig. 9) adapted to be driven by a pawl 92. This pawl is mounted on an arm 93 fixed to a pinion 95 rotatable about shaft 60. The pinion 95 is in mesh with a rack 96 fixed to and movable vertically with the crosshead 22, as clearly illustrated in Fig. 2. The notch in disc 91 is so located and the rotary movement imparted to the associated pawl 92 by means of the rack and pinion is such that the pawl advances the rotary valve drum from position 2 to position 4 in the course of the downward movement of the crosshead. Specifically, the drum reaches position 3 when the crosshead is approximately five-sevenths of the way down and position 4 slightly before the downward movement of the crosshead has been completed.

The movement of valve drum 59 from position 4 to position 5 is by a pressure kicker 72 (Fig. 1) and from position 5 to position 1 by a timer kicker 73. These kickers are similar to kicker 71 except for the difference in radial orientation of the notches in their discs.

The table kicker 71 is under control of a pilot valve 104 (Fig. 2) which normally supplies a head of air from a branch 102 of supply line 103 to pipe 103 extending between the valve and the lower cylinder 86 of the table kicker 71, so that normally its rod 83 is in the up-position, as illustrated in Fig. 4. One of a number of cams 105 on the under side of table 11 moves the valve to an alternative position when the table is rotated to advance a newly charged mold into register with the press plunger, and another such cam restores the valve to its initial position as the table is brought to a stop. With valve 104 in its alternative position it blocks pipe 102 and exhausts pipe 103 to the atmosphere, thereby permitting the pressure applied to the upper cylinder of table kicker 71 to drive the kicker rod and its pawl down. When the table comes to rest, the normal connection of pressure to the lower cylinder is re-established and the kicker rod is raised and advances the rotary valve drum to position 2.

Air for raising the connecting rod of the pressure kicker 72 to advance the rotary valve from position 4 to position 5 is supplied from supply pipe 100 through a branch pipe 106 (Figs. 1 and 5), a pressure kicker valve 120 (Fig. 5), and a pipe 132 extending to the lower cylinder of valve 72. The pressure valve comprises a housing having connected upper and lower cylinders 121 and 122 with the upper cylinder of small cross section compared to that of the lower cylinder. A slide 125 operates in these cylinders and has an upper portion lapped to fit the upper cylinder. That portion of the slide member within cylinder 122 is in the form of a spool having heads 126 and 127. The cylinder 122 has an exhaust passage 128 through its wall, a second passage in communication with branch pipe 106, and a third passage in communication with pipe 132. These passages are so located that, with the slide member 125 in its up-position, head 127 blocks the passage to pipe 106 and head 126 uncovers the exhaust passage 128 thereby exhausting air from pipe 132 so that the rod of the pressure kicker 72 is down. When, however, the slide member 125 is in its down-position, head 126 blocks the exhaust passage 128 and the other passages are in the space between heads

126 and 127, enabling the passage of air from pipe 106 to 132 to effect raising of the pressure kicker plunger to advance the valve 50. The slide member is normally held in its upper position by air supplied to the lower end of cylinder 122 from pipe 106 via a passage 129 in the valve cylinder wall extending into the top of cylinder 121 and through a vertical bore 130 through the slide member to the lower end of cylinder 122. The lower end of bore 130 is constructed so that it is unable to supply air pressure to the lower side of slide member 125 except at a very slow rate. To lower the slide member, the bottom of the cylinder 122 is provided with a poppet valve 133 normally held closed by air pressure in the lower end of the cylinder. This valve, when unseated, rapidly exhausts air from the lower end of cylinder 122 through an exhaust aperture 134, thus enabling air supplied to the upper end of cylinder 121 to force the slide member down, thereby enabling air to be supplied from pipe 106 through cylinder 122 and pipe 132 to raise the pressure kicker to advance the rotary valve drum. The raising of the poppet valve off its seat is arranged to occur when a predetermined pressure has been built up in the crosshead cylinder 30 under piston 31 and is accomplished by a piston 140 within a cylinder 141 in the low pressure chamber 35 adapted to be raised by liquid supplied to the cylinder 141 via a passage 142 in the wall of the rod 32 in communication with the lower end of the crosshead cylinder 30. The piston 140, when raised, transmits this movement to the poppet valve stem via a pressure adjusting mechanism 145 which includes a lever 146 connected to one end of a rod 147. This rod extends outside the low pressure chamber 35 and there carries an arm 148 supporting a shaft 148' having a hand wheel 149 and having threaded thereon a fulcrum block 150 on which the free end of a lever 151, pivoted at 152, rests and whose upper free end is arranged to lift the poppet valve 133. By actuation of the hand wheel 149, the position of block 150 can be readily shifted to modify the leverage between the piston 140 and the poppet valve as required to lift the poppet valve against the pressure in cylinder 122 at any crosshead cylinder pressure at which it is desired to advance the rotary stroke valve to position 5.

The supply of air to the lower cylinder of the timer kicker 73 (Fig. 1) to advance the valve 50 from position 5 to position 1 is from the main air supply line 100 through branch pipe 55 leading to the valve 50, through this valve in position 5 and pipe 57, which extends to the upper end of cylinder 159 of a timer valve 160 (Fig. 3), and thence to a pipe 161 extending to the lower cylinder of the timer kicker 73. The timer valve, however, contains a spool piston 162 which in position 2 and position 3 of the rotary stroke valve is moved to its up-position by liquid 13 driven from the low pressure chamber 35 through a pipe 163 past a check valve 164 and passages 165 and 166 and via a parallel path through a needle valve 167 into the lower end of the timer cylinder 159 at the time air is being supplied to chamber 35. With the space below the lower end of piston 162 filled with liquid and with the rotary stroke valve in position 5, chamber 35 is connected to atmosphere so that the application of air under pressure to the upper end of the cylinder 159 forces the piston 162 downward but the check valve 164 prevents return flow of fluid via it. There are by-pass channels 170 and 171

in valve 160 but these are closed at this time by the lower head of the piston, so that all liquid is forced to pass through the associated needle valve 161 until just before the piston completes its downward travel, at which time the piston affords a passage between the by-pass channels 170 and 171 allowing the piston to suddenly complete its downward movement to connect pipe 161, extending to the lower cylinder of the timer kicker 73, with air from pipe 57 enabling such kicker to advance the rotary stroke valve to position 1. With the valve in this position, air is supplied to pipe 56 once more to force the ram piston to return to its up-position and to effect raising of the crosshead in the manner already made clear.

As above brought out, the application of air to cylinder 41 to raise the ram and the crosshead into the positions shown is through the rotary valve when in its position 1 to which it is advanced by the timer kicker at the conclusion of a pressing cycle. With the valve in this position, air is supplied from the pressure pipe 100 and its branch 55 through the valve 50, as indicated in Fig. 7, to pipe 56 connected with the lower end of cylinder 41. The air introduced into this cylinder, in addition to acting on piston 44 to raise its ram 43 to the position shown, also forces liquid in this cylinder to flow through pipe 65, regulating valve 66, the needle valve 67, pipe 68, and passage 69 into cylinder 30, thereby hydraulically raising it and its crosshead to the position shown. With the valve in position 1, it will be observed from Fig. 7 that pipe 53, extending to the upper end of cylinder 41, and pipe 54, extending to the low pressure chamber, are connected to atmosphere via the rotary valve and pipe 52, so that there is no back pressure in cylinder 41 or chamber 35 to prevent or retard the return of the cross-head or ram. Also, pipe 57, which extends to the timer valve 160 and, at this time, in communication with the lower cylinder of the timer kicker 63, is placed in communication with the exhaust pipe 58 and, accordingly, the timer kicker moves its pawl to the down-position.

As has already been made clear, a pressing cycle is initiated by movement of the rotary stroke valve to position 2 following the registration of a freshly charged mold under the pressing plunger.

In position 2, the branch 55 of supply line 100 is blocked and the pipe 56, extending between the high pressure cylinder 41 and the rotary valve, is brought into communication with pipe 54 leading to the low pressure chamber 35, so that pressure is built up in this chamber until it equalizes that in the charged cylinder 41. This pressure in chamber 35 forces a flow of liquid through by-pass passage 37 and the ram passages 46 and 47, apertures 48, and passage 49 to the under side of piston 31, thus initiating the downward movement of the crosshead 22. By the time the crosshead has been lowered approximately five-sevenths its distance of travel, it has, through the medium of its rack 96, advanced the rotary stroke valve 50 to position 3. In this position of the valve, the upper end of cylinder 41 and the timer valve 160 are still exhausted to atmosphere through valve 50 and, also, the pipe 56 is exhausted to atmosphere via pipe 58. The branch 55 of air pressure supply line 100 is also in communication with pipe 54 extending to the low pressure chamber 35 and, accordingly, the flow of fluid from chamber 35 to

cylinder 30 is continued under an increased pressure.

By the time the crosshead has almost completed its downward travel, it has advanced the 5 rotary stroke valve 50 to position 4. In this position, air from the branch pressure pipe 55, in addition to remaining in communication with pipe 54 leading to the low pressure chamber, is also brought into communication with pipe 53 10 extending to the upper end of cylinder 41 thereby causing the piston 44 to lower the ram 43. When a desired pressure has been developed in the crosshead cylinder, as determined by the setting of the hand wheel 149 of pressure adjusting mechanism 145 (Fig. 6), the piston 140 in the 15 low pressure chamber 35 will rise and through the mechanism already described raise poppet valve 133 of the pressure kicker valve 120 off its seat, thereby causing such valve to operate and 20 supply air to the lower cylinder of the pressure kicker 72 causing it to advance the rotary stroke valve to position 5.

In position 5 of the rotary stroke valve, the 25 branch pressure pipe 55 is brought into communication with pipe 57 extending to the timer valve 160 to effect the operation of the timer kicker 73 to advance the rotary stroke valve to position 1. The remaining pipes 53, 56 and 57 are connected to atmosphere via the pipes 52 and 58. With pipe 30 53 connected to atmosphere, all downward pressure on the crosshead is removed except that exerted by the weight of the assembly. The time period or dwell of the plunger in the mold before its withdrawal therefrom, of course, depends 35 upon the period of delay of advance of the rotary stroke valve from position 5 to position 1 by the timer kicker, as determined by the setting of the needle valve 167 of the timer valve assembly 160.

While in the foregoing there has been shown 40 and described the preferred embodiment of my invention, it is to be understood that minor changes in the details of construction, combination and arrangement of parts may be resorted to without departing from the spirit and scope of 45 the invention as claimed.

What is claimed is:

1. In a pressing apparatus, a crosshead, a crosshead operating cylinder containing a piston, means having passages for conducting fluid 50 to either side of said piston, a ram to force fluid into said cylinder cooperative with said means to successively block certain of said passages to the flow of fluid into said cylinder, a cylinder containing a piston for operating said ram, and 55 valve means operable sequentially to direct a flow of fluid into said first cylinder to actuate it through an initial stage of movement, to direct a flow of fluid to said second cylinder to continue the movement of fluid to the first cylinder and to 60 direct a flow of fluid to said second cylinder to actuate the ram.

2. In a glass working press assembly, a crosshead cylinder containing a piston having an aperture therethrough, a support for the piston having a bore therethrough in communication with said piston aperture and having a passage paralleling such bore and passing through said piston into communication with said cylinder, said support also having a vertical row of horizontal passages extending between its bore and passage, a ram projected into the upper end of the bore of said support and having a one way passage the lower end of which is in communication with said bore, and a fluid chamber in com-

municative relation with the other end of the ram passage.

3. In a press mechanism, a plunger, fluid operated means for lowering and raising said plunger, other means for supplying fluid under pressure to said fluid operated means to lower said plunger, means responsive to pressure developed in lowering said plunger for removing pressure from the fluid operated means, means for thereafter operating said other means to effect raising of the plunger, and a timing device for delaying the raising operation of the plunger for a predetermined time period after pressure has been removed from the fluid.

4. In a press mechanism, a crosshead assembly having a hydraulic power unit for lowering and raising the same, a multi-position valve for controlling the operation of said power unit, a first mechanism for advancing said valve to a position in which it effects the operation of said power unit to lower the crosshead assembly, a mechanical linkage between the crosshead assembly and valve for moving the valve into other positions to further control the downward progress of said crosshead, a second mechanism for advancing said valve to a position for discontinuing the application of power to lower the assembly, a pressure valve for delaying the operation of said latter mechanism until the lowering pressure applied has reached a predetermined value, a third mechanism for advancing said valve to its initial position in which it effects the restoration of said crosshead to its initial position, and a timer valve rendered operative by the multiposition valve in its position for disconnecting power employed in lowering the assembly for delaying the operation of said latter mechanism until after the expiration of a predetermined time.

5. In a press mechanism, a liquid operated crosshead cylinder, a liquid reservoir, a multi-position valve for supplying air under pressure to said reservoir to drive liquid to said crosshead cylinder to move it from one position to another, externally controlled mechanism for moving said valve to one of its positions, a mechanical link-

age between said valve and crosshead for moving said valve to other of its positions, mechanism responsive to a predetermined pressure of liquid in said crosshead cylinder to effect movement of the valve to another position, a timing device whose operation is initiated by fluid fed to it by said valve in the latter position, and means operated through said timing device to advance said multiposition valve to its initial position after the expiration of a predetermined time period.

6. In a press mechanism, a plunger, fluid operated means for lowering and raising said plunger, other means for supplying fluid under pressure to said fluid operated means to lower said plunger, pressure responsive means operated by pressure developed in the lowering of said plunger for removing pressure from the fluid operated means, means for thereafter operating said other means to effect raising of the plunger, a timing device for delaying the raising of the plunger for a predetermined time period after pressure has been removed from the fluid, and means for supplying liquid to said timing device while the plunger is being lowered to prepare the timing device for operation subsequent to the removal of pressure from the fluid operated means.

7. In a glass working machine a crosshead actuating assembly including a piston and cooperative cylinder, a reservoir in communication with said cylinder containing a liquid, a reservoir charged with compressed air, a compressed air supply line, a multiposition valve, means for operating said valve to bring said charged reservoir into communication with said first reservoir whereby the compressed air supplied by the charged reservoir will force liquid from said first reservoir into said cylinder and thus effect an actuation of the crosshead and means responsive to the actuation of the crosshead for operating said valve to establish direct communication between said air supply line and said second reservoir whereby more of the liquid in said first reservoir is forced into said cylinder to effect a further actuation of the crosshead.

DAVID E. GRAY.
